FIG. 7

UNITED STATES PATENT OFFICE.

NILS EMEL NORSTROM, OF CHICAGO, ILLINOIS.

PARTY-LINE TELEPHONE-EXCHANGE.

1,326,212.

Specification of Letters Patent. Patented Dec. 30, 1919.

Application filed March 20, 1916, Serial No. 85,279. Renewed April 22, 1918. Serial No. 229,938.

To all whom it may concern:

Be it known that I, NILS EMEL NORSTROM, a citizen of the United States of America, and a resident of Chicago, county of Cook, 5 and State of Illinois, have invented certain new and useful Improvements in Party-Line Telephone-Exchanges, of which the following is a specification.

My invention relates to party line tele- 10 phone exchanges, and has for its object improvements in such exchanges.

In the accompanying drawings

Figure 1 is a transverse section of a central office keyboard suitable for operation in 15 this exchange, only so much of said device being shown as is deemed necessary to explain the operations of the exchange;

Fig. 2 is an enlarged plan of part of the contact arms shown in Fig. 1;

Fig. 3 is a side elevation of three of the contact arms shown in Figs. 1 and 2;

Figs. 4 and 5 are section and perspective views, respectively, of one of the spirally arranged wiper arms shown in Fig. 1;

Fig. 6 is a detail of the ratchet wheel and some of the contact springs operated by the switching mechanisms at the local stations; and

Fig. 7 is a diagram of the exchange, showing one local station at the upper right hand of the drawing, and lines leading to other local stations at the lower left hand corner.

The keyboard, or calling device, shown in Fig. 1 consists of a suitable frame having two rows of insulated keys 10 which are properly numbered to represent different stations on a party line. There is presumed to be one such keyboard at each operator's position in the exchange, but the diagram 40 illustrates connections to only one of them.

Beneath each row of keys 10 is a shaft 11 on which are loosely mounted contact arms 114, there being one such arm for each key 10. Associated with each arm 114 is a collar 12 secured to the shaft 11 by set screw 13. A spring 14 on each collar serves to normally depress the inner end of the associated arm 114. On the lower end of the stem for each key 10 is a head 15 which, when the 50 keys 10 are in elevated position as shown in Fig. 1, engages the upper end of associated arm 114 to push it outward and consequently to raise the inner end. When, however, a key 10 is depressed, the spring 14 55 connected to the corresponding arm 114 moves the inner end of the arm downward

and the upper end inward so that the hook 16 drops over the head 15 and holds the key depressed until released as hereinafter described.

In the center of the calling device is a shaft 150 on which are spirally arranged a series of wiper arms 115. These wiper arms consist of sheet metal 17 formed around blocks 18 held to shaft 150 by set 60 screws 19. These wiper arms have the outer end of the sheet metal 17 curved as shown in Fig. 5, and are arranged longitudinally on shaft 150 so that each wiper arm may engage two contact arms 114 as shown in Fig. 65 2. Each block 18 has its outer end cut away as shown at 20 so that the wiper arm will make electrical connection with a contact arm before the block engages the pointed end 21 of the contact arm. The shaft 150 is 70 driven in the direction of the arrow by a magnet and ratchet wheel, as shown in Fig. 7. As the shaft 150 advances step by step, a wiper 115 first engages a contact arm 114, (if it is at the time in a depressed position), 75 and then pushes the inner end of the arm upward to release the engaged head 15 and permit the depressed key 10 to rise to normal position. As the wiper arms are spirally arranged on the shaft 150, it will be evident 80 that the number of steps which the shaft makes before a key is released will depend upon what key 10 is depressed.

The switching mechanisms at the local stations are of an ordinary and well known 90 kind, and do not need description. However, there is a characteristic of such switching mechanism which calls for special notice because it has a bearing upon the operation at the central office. The matter referred to 95 is illustrated in Fig. 6. The ratchet wheel 22 is mounted on the shaft 23 and is driven by a pawl 24. Adjacent to the wheel 22 are some contact springs, one of which carries a piece of insulation which engages a flattened part of shaft 23. The flattened part of the shaft acts as a cam to move the central spring from electrical connection with the upper spring to electrical connection with the lower one. The ratchet wheel has 100 fine teeth and is operated by impulses sent from the central office. Owing to the fineness of the teeth, one step of the ratchet wheel is not enough to shift this connection with certainty unless the adjustment of the 105 spring is made with extreme care. To overcome this difficulty in the ordinary local sta-

tion switching mechanism and to avoid such extreme delicacy of adjustment, the calling device at the central office is made so that it will never send out less than a plurality 5 of operating impulses, no matter what station may be called.

The switching mechanisms at the local 10 stations are operated by polarized magnets and so arranged that impulses in one direction advance the mechanisms, while impulses in the opposite direction release them. For each party line there is a similar mechanism 15 87 which operates contacts which will be explained in explaining the operation of the exchange.

At the central office there is commutator 20 impulse sender S driven by a motor generator MM¹, the current for operating which comes from a battery X. This battery is the regular central energy storage battery used in common battery exchanges. The impulse sender distributes impulses from the generator part M¹ as will be described.

Also at the central office are a generator 25 99, certain keys, magnets, contacts and connections, all of which will be understood from the description of the operation of the exchange.

It will be assumed that the subscriber at 30 the local station shown in the upper right hand corner of Fig. 7 calls central, and that the operator responds and makes the desired connection.

To call central, the subscriber turns the 35 crank of his generator when a current flows: G¹—31—32—33—34—35—36—37—38—39—40—41—42—43—44—45—46—47—48—49—50—51—G¹.

This operates drop 38 to call operator, 40 who inserts plug in jack and presses listening key K, whereupon the talking circuit between calling subscriber and operator is as follows: receiver at local station—S¹—52—hook—53—54—55—34—35—36—56—plug 45 and operator's set—45—46—47—48—49—50—51—receiver.

To call another subscriber on the same party line, the operator presses the key 10 on her calling device which corresponds to 50 the station to be called. She also presses key K¹. The completed circuit is:—X—57—58—59—60—61—62—63—64—65—66—M—ground—X.

The motor M drives the 100-volt dynamo 55 M¹ and the impulse sender S. From these impulses flow to operate magnets C and D, 60 and the stepping up coils at the local stations, and a corresponding stepping up device at the central office. The first circuit is:—M¹—67—68—69—70—ground to the local stations on the line—71—72—48—65 47—46—45—73—74—75—76—77—78—79—

D—79—80—81—82—83—84—85—86—M¹. There is also a branch to ground at central through magnet 87 and wire 88 to 45 where it joins the previous circuit. The impulses in this case are in the release direction through the stepping up magnets, the object being to insure that all switching mechanisms at the local stations, and the corresponding one 87 at the central office, shall be in normal position when stepping up impulses begin. 70 75

The first impulse through magnet D closes 90 to 91, when a circuit is completed as follows:—X—57—58—59—B—89—90—91—92—ground—X. Magnet B closes ground 80 connection for itself at 93—94, so that it is independent of the connection closed by D, and also closes for C a circuit as follows:—M¹—67—68—69—70—ground—92—93—95—C—82—83—84—85—86—M¹. 85

The impulses through C advance the ratchet wheel 151 and shaft 150 so as to bring the wipers 115 in succession to position to engage any contact arms 114 which may have been depressed by the operator 90 pressing one or more of the keys 10. On the shaft 151 is a loose arm 152 located between and driven by two pins on the wheel 151. There is a little play between the arm 152 and the pins in the wheel so that two or more steps will be made by the wheel before the adjacent pin thereon engages and moves the arm 152 from its normal position. The arm 152 has, on its outer end, a piece of insulation on which rests the end of the spring 95 100 80 when the arm is in normal position. When, however, the arm 152 has moved from under spring 80, electrical connection shifts from 81 to 98. In this condition the release impulses previously described as passing 105 from 80 to 82 by way of 81 will thereafter pass by way of the resistance R. These release impulses through resistance R continue, and alternating with them are operating impulses as follows:—M¹—67—68—69—110 96—97—98—80—79, and so on over the same circuit but in the operating direction through magnets 71 and 87. In other words, operating impulses and release impulses flow alternately from the dynamo M¹ through 115 the stepping up coils. The operating impulses are full strength, while the release impulses flow through the resistance R and have only sufficient strength to neutralize the residual magnetism in the coils and assist the reverse movement of their armatures. 120

During this operation, magnet C continues to receive operating impulses which are simultaneous with the release impulses through the stepping up coils, but which 125 pass around resistance R. These impulses through C advance shaft 150 and wipers 115 as before described. If we assume that the key 10 on the keyboard which the operator pressed was for station No. 10 on the line, 130

then, after the stepping up coils have made their ninth step, magnet C brings the tenth wiper 115 into electrical contact with the tenth contact lever 114. This electrical connection remains while the stepping up coils make their tenth step, immediately after which the next step by magnet C causes the tenth wiper to push up the tenth contact lever 114 to break the electrical connection at 10 this point and permit key 10 to rise.

At the local stations, each forward step causes spring 32 to engage spring 106, and at station No. 10 the tenth step causes arm 118 to push spring 104 into engagement 15 with contact 103. When this occurs, a current flows:—generator 99 at central—100—63—ground to local station No. 10—cut-in coil 101—102—103—104—105—106—32—33—34—35—36—56—107—108—109—110—20 111—112—113—114—115—116—117—99.

At the beginning of the stepping up movements at the local station, the cam on shaft 23 moved spring 50 from electrical connection with spring 49 to connection with 25 contact 134. A similar action also occurs for switch 87 at the central office. At the different local stations on the line, the arms 118 move spring 104 in succession, one at each step of the switching mechanisms. Consequently 30 the impulse last described for operating the lock-in coil 101 goes only through the selected station No. 10. The operation of this coil shifts the electrical connections just above its armature and 35 thereby connects the selected station telephonically to the line.

The rise of key No. 10 on the calling device breaks the circuits, either directly or indirectly, for the magnets A, B and C, and 40 the motor M. The operation of the switch 87 at central, however, provides another circuit as follows:—X—119—120—121—122—123—124—125—66—M—ground—X. The lamp 124 in this circuit provides resistance 45 which permits the motor to continue running, but at a reduced speed.

When the circuit through magnet A is broken as described, the contact springs moved thereby return to their normal position, whereupon a current flows:—99—100—50 126—127—77—76—75—74—73—45—46—47—48—128—129—130—ringer 131—53—54—55—34—35—36—56—107—108—109—110—111—112—113—114—115—116—117—99. This calls the subscriber, and the ringing continues as long as the operator holds key K¹ depressed. This key is of the standard type used in telephone exchanges, but is arbitrarily illustrated in the drawing.

50 In the lower part of Fig. 7 is shown a plug P adapted to be inserted in a jack J connected to another party line L. It will be evident that with plug P in jack J another party on line L might be called by the 55 process described. With both plugs in their

jacks a party on one line can talk to another person on the other line. Consequently, in giving the talking circuit it is only necessary to trace that which extends beyond one of these jacks and through a local station. 70 Beginning at the receiver in the local station previously described as called, the talking circuit is:—receiver—S¹—52—53—54—34—35—36—56 over cord circuit and the other line back to 45—46—47—48—128—75 133—134—50—51—receiver.

To ring off:—G¹—31—32—33—34—35—36—56—107—135—136—137—138—139—140—141—74—73—45—46—47—48—128—133—134—50—51—G¹. This operates clearing-out drop 138 to inform the operator that the conversation is ended.

The operator removes plug from jack to permit 45 to close to 44, when a current flows:—M¹—67—68—69—70—ground to all 80 local stations on the line—71—72—48—47—46—45—44—43—42—41—142—143—144—82—83—84—85—86—M¹. There is also a branch through 87 to 44. These impulses are, at first, of low voltage, due to the slow 90 running of the motor as before described. The armature of switch 87, however, is arranged to have play between stiff springs so that the low voltage from M¹ may move the armature far enough to close contact 95 145. This closure shunts the lamp 124 so that the motor may get full voltage from battery X. This permits the motor to increase its speed and cause dynamo M¹ to send impulses of full voltage over the last 100 given circuit, which impulses are in the release direction. The central office switch 87 is provided with an unusually heavy ratchet wheel, or other heavy moving parts, so that it will be more sluggish in its release action 105 than are the switches at the local stations. This permits the switches at the local stations to return to normal position sooner than switch 87. Upon release of switch 87, the motor circuit is broken at 121—122, and 110 the motor stops. The same release also bridges the drop 38 by closing contacts 40—41. The contacts 40—41 are used to cut the drop 38 from the line so that contact 44 may be used to carry release impulses upon 115 removal of the plug without causing the drop 38 to flutter.

When a call is made on a party line, all stations on the line have their springs 50 moved from contact 49 to contact 134. At 120 the called station, the lock-in coil 101 has been operated. At uncalled stations the contacts operated by this coil are in their normal position. If an uncalled subscriber attempts to call central when the line is 125 busy, his generator will be shunted as follows:—G¹—31—32—33—55—54—53—145—133—134—50—51—G¹. If, however, the subscriber should press his emergency key 54, the shunt would be cut out and the cir- 130

cuit would be through the clearing out drop 138 as given for ringing off, except last part which is:—47—48—160—161—54—53—145 133—134—50—51—G¹.

5. It will be observed that the shunt just given for the magneto or generator G¹ contains no resistance when the line is busy and the subscriber does not press the emergency key. Under these conditions a very great current flows over this dead shunt when the generator crank is turned, and this great current causes the crank to turn heavy and thus indicate to the subscriber, by the sense of feeling, that the line is busy. Heretofore similar party lines have had no such shunt for the magneto, but the circuit has been open when the line was busy and the emergency button not pressed. Under these circumstances no current would flow, and the difference between no current and the small amount necessary to call central is not enough to indicate by feeling that the line is busy.

At the upper part of that portion of the drawing which shows the local station are two binding posts 300, and farther down on the drawing are four binding posts 301. The apparatus included between binding posts 300 and binding posts 301 is the lock-out apparatus, and is inclosed in a locked and sealed case or box. The apparatus below binding posts 301 is that contained in the ordinary telephone box. The party line connections are made at posts 300, and posts 300 and 301 are secured to the case containing the lock-out apparatus.

Emergency keys, such as 54, have heretofore been used in party line exchanges, and to prevent an uncalled subscriber from listening in on the line by pressing this button, there has been provided a shunt for the receiver. This shunt has, heretofore, always been one of the exposed wires extending from the case containing the lock-out apparatus to the telephone box. As this wire served no purpose other than that of shunting the receiver in an uncalled station, it was always possible to release it from one of its binding posts without disturbing the operation of the apparatus or giving any appearance of change. By so doing an uncalled subscriber could press his emergency key and listen on the line. The reason why this has heretofore been possible is that the emergency key was placed on the same side of the line as the contacts operated by the cut-in-coil, (open at all uncalled stations), and was used to close the circuit around those contacts to enable the subscriber to send a magneto current to central. Prevention for listening was due solely to the shunt which a subscriber might release or cut because exposed.

In the present case I have removed the emergency key to the other side of the line so that it does not close the circuit around the

contacts operated by the cut-in coil, and use part of the talking shunt as part of the magneto circuit for calling central. This talking shunt in an uncalled station is:—Receiver — S¹—52—53—145—133—134—50—51—receiver. Cutting the shunt connection 145 would cripple the connection for emergency calling without enabling the uncalled subscriber to listen on the line because the emergency key does not close around the open connections. Consequently I may place this shunt 145 in either an exposed or an unexposed position without affording means by which an uncalled subscriber may listen on the line. I have, however, placed it entirely within the sealed box containing the lock-out apparatus, which heretofore could not be done.

Returning now to the impulse sender S, it will be seen that this is a device for supplying or sending alternating impulses to ground, and for separating the impulses so that plus impulses are sent over one line and minus impulses over another line. Thus, if we consider impulses as flowing from the sender, positive impulses would flow from the brush 96, and negative impulses from brush 83. One keyboard having keys 10 and 10^a is shown as connected to the brushes 96 and 83, and to the battery X. It will be evident that the impulses flowing from the sender and controlled by the keyboard are not influenced by the presence or absence of another keyboard connected to brushes 96 and 83, and battery X. Consequently, other keyboards with their associated parts may be connected to the same brushes and calls may be made simultaneously over other lines without causing confusion. Connections completed are shown for one keyboard, and other connections are shown at 302 which may be extended in the same way to another keyboard. In the construction and arrangement shown, one impulse sender S, and one main battery X are sufficient for an entire exchange, no matter how many keyboards there are, or how many party lines are served by those keyboards. The impulse sender, as far as it is individually concerned, furnishes full strength alternating impulses alike to one or a plurality of keyboards. Each keyboard with its associated parts sorts out these impulses for its own line so that either full strength release impulses or full strength stepping impulses flow over the line as wanted. Thus, stepping impulses may flow over one line and simultaneously therewith release impulses may flow over another line, all impulses coming from one and the same sender. The keyboard also governs the flow of impulses over the line so that release impulses of reduced strength will alternate with the full strength stepping impulses.

In calling over two lines at the same time, 130

plugs 73—107 and P are inserted in the jacks of the respective lines, and the keys K¹ and K² are pressed. In this condition the stepping up coils of both lines are connected together through the tip sides of both plugs, (73 and 305), and the impulses from the sender S come to the center of this connected line through the wires 76. Consequently, each impulse operates over both lines to produce simultaneous operation of the stepping up coils on both lines. Heretofore, when calls were made over two lines, impulses were sent alternately, first over one line and then over the other. The present arrangement which connects the two lines as described saves in time required for calling and also in equipment.

While pressing both keys K¹ and K² connects the tip sides of plugs together, that action separates the sleeve sides. By referring back to the circuit from generator through the cut-in coil 101 it will be seen that that circuit goes through the sleeve side 107 and the contact arm 114 controlled by the key 10 on the keyboard. A precisely similar circuit may be traced from the sleeve side of plug P to the contact arm 114^a on the opposite side of the calling device. The contact arms 114 on one side and 114^a on the other are insulated from each other so that a contact made by one wiper 115 to send out an impulse through the sleeve side of one plug does not necessarily involve a similar impulse through the other plug. If the contact arms are directly opposite each other, then the wiper 115 will connect to both at the same time and cut-in impulses will flow over both lines at once. If, however, the contact arms 114 and 114^a which are depressed are at different longitudinal positions in the calling device, then they will be operated by different wipers 115.

As previously explained, the wiper 115 pushed up contact arm 114 thereby opening contacts 57—58 to break the circuits for magnets A, B and C, and motor M. But the contacts 57—58 are on spring plates which extend across the calling device, and if we assume that the key 10^a represents station No. 15 on the other line, then the arm 114^a will be farther along in the calling device and the circuits for these magnets and the motor will not be broken until the corresponding wiper 115 comes to and passes its central upright position.

What I claim is:

1. A source of alternating impulses, a party line over which such impulses may flow, a calling device arranged to control the distribution of the impulses to the line, and means for controlling the calling device by the impulses.

2. A source of alternating impulses, a party line, a calling device arranged to distribute the impulses from the source in a

predetermined arrangement to the party line, and means for operating the calling device by the impulses.

3. A battery, a motor-generator driven thereby, a calling device operated by impulses from the motor-generator, and means by which the calling device controls the number and distribution of impulses from the motor-generator. 70

4. A battery, a motor-generator driven thereby, a circuit over which a current may flow from the generator, a commutator driven by the motor and serving to transform the current from the generator into alternating impulses flowing over the line, and 80 means controlled by the commutator for reducing the voltage of each alternate impulse.

5. A battery, a motor-generator driven thereby, a calling device, a circuit over 85 which impulses from the motor-generator operate the calling device, a party line arranged to receive impulses from the motor-generator, and means by which the calling device controls the impulses to itself and to 90 the party line.

6. The combination with two party lines each having a plurality of local stations thereon and each station having a step-by-step mechanism connected to the line, and 95 a cord connecting the two lines, of a source of electricity connected to one side of the cord, and means by which impulses from said source are caused to flow over both lines simultaneously to cause all step-by-step 100 mechanisms of both lines to move in synchronism.

7. The combination with two party lines, and a cord having the same side simultaneously connected to both lines, of a wire connected to the connecting side of the cord, a source of electricity, and means by which impulses from said source are caused to flow over said wire and cord to cause simultaneous operation of electrical apparatus at all 110 stations on both lines. 105

8. Two party lines each having local stations with step-by-step apparatus thereat, a central office to which said lines are connected, an impulse sender at said office, and 115 means by which each impulse from said sender causes the same operation of the step-by-step apparatus of all stations of both lines.

9. The combination with two party lines, 120 an impulse sender, a calling device controlling the impulses from said sender, and a generator, of a cord serving to connect the two lines, means by which one side of said cord connects corresponding branches of the 125 two lines together so that impulses from said sender will flow alike over the connected branches, and means by which the other side of said cord separates the other branches of the two lines so that impulses from said gen- 130

erator will flow at different times over the separated branches.

10. The combination with two party lines, a source of alternating impulses, and a calling device for distributing such impulses in a predetermined manner to said lines, of a cord provided with means for connecting together corresponding branches of each line and separating other branches, connections 5 from the calling device to one branch of the cord so that given impulses will flow simultaneously over the connected branches, and other connections from the calling device to the other branch of the cord so that impulses 10 will flow at different times over the separated branches.

11. A party line terminating in a jack in a central office, switching mechanisms at local stations on the party line, a special 20 switching mechanism at the central office and also connected to the party line, a line drop at the central office and operable from the stations on the line, means by which upon insertion of a plug in said jack operating impulses may be sent to all of said switching mechanisms, means by which release impulses are automatically sent to all switches upon removal of the plug from the jack, and a connection for said drop controlled by the special switching mechanism 25 so that the said drop has its circuit broken during the sending of such release impulses.

12. The combination with a party line provided with a jack in which a plug may 30 be inserted and removed, and a line drop operable from local stations on the line, of means for sending impulses over the line when the plug is not in the jack, and means by which such impulses are prevented from 35 affecting the line drop.

13. A plurality of party lines extending to a central office, a source of alternating impulses at the central office, said source being provided with connections to a plurality of 40 calling devices, a calling device attached to a pair of such connections, a cord connecting the calling device to one of the party lines, and means by which the impulses received by the calling device are modified and distributed 45 to the line to which it is connected independently of the manner in which the same impulses are modified and distributed to some other line connected to some other calling device.

14. A party line, switches connected to the party line and advanced by impulses in one direction and released by impulses in the other direction, a source of alternating impulses, means by which upon connecting said 50 source to the line impulses of full voltage in the release direction will flow through said switches, and means by which upon the completion of a small number of such impulses a resistance will be automatically placed in

the circuit for such impulses and other impulses of full voltage in the operating direction will alternate with the reduced impulses in the release direction. 65

15. A party line, a source of alternating impulses, means by which upon connecting the line to the source impulses in one direction will flow over the line, and automatically operating means for inserting resistance between the source and the line upon the completion of a predetermined 70 number of impulses. 75

16. The combination with a party line, and means for sending electrical impulses thereover, of means controlled by the impulses for reducing the voltage of all impulses following a predetermined number 80 of impulses.

17. A central office, a party line connected to the central office and having lock-out apparatus and a receiver at each one of a plurality of local stations on the line, a connection at each local station serving to shunt the receivers at stations locked out, a generator at each local station, a signal at the central office adapted to be operated by the generator, and a manually closable circuit for said generator and signal, said circuit being composed in part of the shunt for the receiver at the same station. 90 95

18. In a lock-out party line system having a central office and a plurality of local stations on a party line connected thereto, a telephonic shunt for each station locked out, a generator at each local station, and a manually operated emergency connection 100 for completing a signaling circuit from a locked out station to the central office, said circuit being composed in part of the telephonic shunt for the station.

19. In the local station circuits of a party line system, binding posts 300 serving as connections between the line and the local station, other binding posts 301 serving as connections to the normal local station telephone apparatus, and a telephonic shunt for 110 the station consisting of a connection located between posts 300 and 301. 105

20. A party line terminating in a jack in a central office, switching mechanisms at local stations on the party line and advanced 115 by impulses in one direction and released by impulses in the other direction, a special switching mechanism at the central office and also connected to the party line, a source of electrical impulses for operating all of 120 said mechanisms, and automatically operating means by which all impulses flowing from said source over the line will be in release direction when the jack has no plug therein. 125

21. A party line terminating in a jack at a central office, switching mechanisms at local stations on the party line and ad-

vanced by impulses in one direction and released by impulses in the other direction, a special switching mechanism at the central office and also connected to the party line, a source of electrical impulses for operating all of said mechanisms, and means by which upon said special mechanism being advanced from its normal position when the jack has no plug therein impulses from said source in release direction will be automatically sent over the line.

22. A party line connected to a central office, switching mechanisms at local stations on the line, connections at each station 15 for establishing a magneto circuit and a talking circuit for the station, means controlled from the central office for advancing the switching mechanisms of all stations and for connecting selected stations telephonically to the line, means by which upon the advance of the mechanism at an unselected station there will be established a shunt for the magneto circuit and a separate shunt for the talking circuit, and an emergency key by which the subscriber at a station 20 may cut the shunt for the magneto cir-

cuit without affecting the shunt for the talking circuit.

23. A party line connected to a central office, connections at each station on the line 30 for establishing magneto and talking circuits for the station, means controlled from the central office for establishing a separate shunt for each circuit, means under the control of a subscriber for cutting the magneto 35 shunt at his station, and means under the exclusive control, of an operator at the central office for cutting the talking shunt.

24. A party line connected to a central office, a magneto at each station on the line 40 by means of which the subscriber thereat may call the central office, and means controlled from the central office for connecting a selected station telephonically to the line and for establishing a shunt at each other 45 local station for the magneto thereat, said shunts having no resistance therein other than that existing in the connections forming them.
